United States Patent Office

Des. 189,448
Patented Dec. 20, 1960

189,448

AUTOMOBILE

Raymond Loewy, New York, N.Y., assignor to Raymond Loewy Associates, New York, N.Y., a partnership

Filed Jan. 21, 1958, Ser. No. 49,341

Term of patent 14 years

(Cl. D14—6)

FIG. 7.

FIG. 8.

FIG. 9.

FIG. 4.

Figure 1 is a front perspective view of an automobile, embodying my new design;

Fig. 2 is a cross-sectional view taken on line 2—2 of Fig. 1;

Fig. 3 is a cross-sectional view taken on line 3—3 of Fig. 1;

Fig. 4 is a cross-sectional view taken on line 4—4 of Fig. 1; and

Fig. 5 is an enlarged perspective view of the panel shown in full lines in Fig. 1.

The essential features of my design reside in those portions shown in full lines.

I claim:

The ornamental design for an automobile, as shown and described.
